COFFEE PERCOLATOR

Renato Piovani, Via Donato 66/3, Bologna, Italy

Continuation-in-part of design application Ser. No. 20,488,
Dec. 15, 1969. This application Aug. 18, 1970, Ser.
No. 24,557

Term of patent 14 years

Int. Cl. D7—02

U.S. Cl. D44—26

FIG. 1

Des. 222,379

PAGE 2

FIG. 2

FIG. 3

FIG. 4

FIG. 1 is a front perspective view of a coffee percolator showing my new design.

FIG. 2 is a rear perspective view thereof.

FIG. 3 is a top plan view thereof.

FIG. 4 is a bottom view thereof.

This is a continuation-in-part of my application D. 20,488 of Dec. 15, 1969, now abandoned.

I claim:

The ornamental design for a coffee percolator, substantially as shown and described.
